FASTENING DEVICE FOR PERCOLATOR TOPS

William G. Billerman, Newark, N. J.

Application April 4, 1930, Serial No. 441,457

4 Claims. (Cl. 53—3)

This invention relates to an improved means for securing the glass tops on the lids of coffee percolators.

The article is a simple band of metal which is placed around the flange of the top that projects down through the lid and is turned to engage the lugs on the flange. The band engages the bottom surface of the lid and holds the top against rattling and against accidental dropping out 10 when the pot is tilted. The article can be quickly attached or removed and is adapted for securing the top firmly in place irrespective of the slight differences that exist in the space between the lugs on the top and the under-face of the lid.

15 The invention is illustrated in the accompanying drawing in which Figure 1 is a section of a lid and the top with the fastener in position. Figure 2 is a bottom view of the part shown in Figure 1, and Figure 3 is a side view of the fastener. Figure 20 4 is a perspective view of a modified form of fastener.

The top is shown at 10 and the lid is represented at 11. The top is of the usual kind with a flange 12 that extends through an opening in the lid and the flange has small projections 13 which are passed through the recesses or notches 14 at the edges of the opening in the lid when the flange is passed through the opening. The top is turned to clear the notches after assembly.

30 The lid is made of soft metal and the turned or partly crimped edge 15 of the lid sometimes becomes bent, the top fits loosely and is apt to fall out when the pot is tilted in pouring.

To lock the top in place, to brace the edge 15 and make a tighter joint between the top and the under surface of the lid I provide a band 16 which is turned on the flange 12 and holds it against rotation and removal and locks the top in place. The band is provided, in one form with threads 17 40 which are screwed on the small projections 13 of the flange. The screw threads 17 may be a double thread or it may be a single thread with a pitch to enable it to engage both projections 13. When screwed up tightly the band firmly seats the dome against the lid, the bead 18 tightly engaging the crimped part 15 and the band itself firmly engaging the crimped edge 15, thus forming another seal and also bracing the crimped edge and thus preventing rattling.

45 Another form of band is shown in Figure 4 in which form the bayonet slots 19 are formed in the band, the part 20 being slightly inclined to force the parts tightly together.

This band is simple to install and is an economical means of fastening the top in place.

I claim:—

1. The combination of a lid having an opening with a downwardly turned edge, a top adapted to rest on said lid and having a flange projecting through the opening and having a projection on the flange, with a non-resilient continuous ring having a locking part to engage the projection to force the top into close contact with the upper face of the lid and force the upper edge of the ring in close contact with the bottom face of the lid.

2. The combination of a lid having an opening with downwardly turned edges, a top having an annular bead to rest on the top face of said edge and having a flange projecting through the opening, the top having a projection at the bottom of the flange, the edge of the opening having a notch to allow the passage of the projection, with a band surrounding said flange and having a thread to engage the projection to cause the top edge of the band to engage the bottom face of the lid and to cause the bead on the top to engage the top face of the lid.

3. The combination of a lid having an opening with downwardly turned edges, a top having an annular bead to rest on the top face of said edge and having a flange projecting through the opening, the top having a projection at the bottom of the flange, the edge of the opening having a notch to allow the passage of the projection, with a non-resilient continuous band surrounding said flange and having means co-operating with the projection to cause the band to engage the bottom face of the lid with its top edge and to cause the bead on the top to engage the top face of the lid.

4. In a percolator cover, the combination with a lid having an opening therein for receiving a glass percolator top, of means on said top for limiting the movement of said top into the opening and having a stud on the portion projecting through the top, and a continuous screw-thread band fitting said projecting part with its thread fitting the stud whereby the band when screwed on tightly holds the parts in close contact.

WILLIAM G. BILLERMAN.
